UNITED STATES PATENT OFFICE.

WILLIAM GAGNIER, OF MILWAUKEE, WISCONSIN.

DESIGN FOR A PESSARY.

SPECIFICATION forming part of Design No. 32,566, dated April 24, 1900.

Application filed March 27, 1900. Serial No. 10,401. Term of patent 7 years.

To all whom it may concern:

Be it known that I, WILLIAM GAGNIER, a citizen of the United States, residing at Milwaukee, in the county of Milwaukee and State 5 of Wisconsin, have invented and produced a new and original Design for a Pessary; and I do hereby declare the following to be a full, clear, and exact description of the same, reference being had to the accompanying drawings, forming a part thereof.

In the said drawings, Figure 1 is a side elevation; Fig. 2, a vertical sectional view taken on the line 2 2 of Fig. 1, and Fig. 3 an under side plan view of a pessary embodying my 15 new design.

My design relates to the new and original shape or configuration of the article.

The leading or essential feature consists in the unitary design for a pessary made the 20 subject of illustration, comprising the shape of the vertical round hollow column A, with central circular concave depression B at the top thereof surrounded by an annular con-

vex border b, merging into the straight lines of the column A, which lines adjacent to the 25 base merge into the outwardly-flaring side lines c c of the base, the side portions C C of the base being formed on convex rounded lines merging into the concave rounded lines of the front and rear portion D D of the base, 30 while the base-line proper in side view follows the line of a double ogee, as shown at d e d, the central part e of which is at a lower plane than that of the ends d d of said line.

Having thus described my invention, what 35 I claim as new, and desire to secure by Letters Patent, is—

The design for a pessary, substantially as herein shown and described.

In testimony whereof I affix my signature 40 in presence of two witnesses.

WM. GAGNIER.
